UNITED STATES PATENT OFFICE.

WILLIAM BRIGGS, OF MANCHESTER, ENGLAND.

APPARATUS FOR PRINTING TRANSFER-DESIGNS ON PAPER IN TWO OR MORE COLORS OR MEDIUMS.

No. 923,242.

Specification of Letters Patent.

Patented June 1, 1909.

Application filed August 22, 1908. Serial No. 449,856.

To all whom it may concern:

Be it known that I, WILLIAM BRIGGS, a subject of the King of Great Britain and Ireland, residing at 71 Cannon street, Manchester, in the county of Lancaster, England, manufacturer, have invented new and useful Improvements in and Connected with Apparatus for Printing Transfer-Designs on Paper in Two or More Colors or Mediums, of which the following is a specification.

My invention is connected with the printing of transfer designs on paper in two or more colors and to apparatus for accomplishing this object.

It is a well known plan to print transfer designs on paper in a single color which is afterward ironed off on to a fabric whereby the design is transferred. Hitherto small designs in two colors have been printed separately by blocks on transfer paper to a limited extent, but the general plan has been to have the separate colored portion of a design on separate transfer papers, and to transfer each portion of the design separately. This necessitates two processes, two sets of transfer papers, and difficulty in insuring correct register.

Under this invention I seek to print in two or more colors at one operation upon a single paper and continuously by the operation of a single machine, the paper being passed therethrough and printed in the two colors so that the colors in the design will register correctly or sufficiently so for all practical purpose. I believe it to be quite new to aim at getting a continuous and mechanical production of a single paper printed in two or more colors.

I will indicate the manner of production and the class of apparatus which I purpose using, and which apparatus I shall describe in detail.

It is first of all desirable to incorporate with the color first printed some substance which will cause the first color to dry more rapidly and an incorporation of shellac will serve this purpose, but other substances may be found equally useful for such object. Then the paper bearing the first imprint must have a sufficiently long traverse to give the color time to set or dry before the paper receives the imprint from the second rotating die or printing cylinder. To insure correct

"register" it is necessary to be able to adjust either or both of the rotating dies or printing cylinders circumferentially, and endwise, and preferably I have this power of adjustment with respect to both cylinders. I print by the cylinders against backing rollers or drums, and these must be carried so as to allow of ready adjustment toward or from the printing cylinders, and it is best that a motion be fitted to allow of the two bearings being adjusted to an absolutely equal or uniform extent. Then I find it desirable to print both colors hot and the temperature of the first color may be higher than the second. All these factors are to a certain extent necessary, and having specified such, I will now proceed to describe the apparatus used by me, with the help of the attached nine sheets of drawings.

With regard to the said drawings, Figure 1 is a diagrammatic side elevation of the two color printing apparatus, which is broken in length and elsewhere for want of space on the sheet. Fig. 2 is an enlarged fragmentary side elevation showing the means for supporting and actuating the 1st rotating die or printing cylinder and the means for accurately and uniformly setting-up or shifting the backing roller. Fig. 3 shows an end view of the doctor which holds the color and contacts with the printing cylinder. Fig. 4 is a plan of said doctor broken in length. Fig. 5 is a front view of the printing cylinder supporting and adjusting means, the gear driving wheel for same, and the worm gear for adjusting the printing cylinder circumferentially, and other details. Fig. 6 indicates by a front view how the 1st spur pinion in the train of three pinions for driving the 1st printing cylinder is actuated, and also the way in which the upright shaft conveying motion to the 2nd printing cylinder is driven. Fig. 7 is a broken plan view of the back and front shafts with pulleys, and indicates also the driving for the train of 3 pinions and for the upright shaft. Fig. 8 is a rear elevation of the back shaft, certain pulleys and sheaths, and the strap fork, stop rod &c. Fig. 9 shows a side elevation of the gear and parts in connection with the 2nd revolving die or printing cylinder. Fig. 10 indicates in detail a guide rod or bar adjustable angularly, and of which one, two, or more are used to guide the paper. Fig. 11

is a detail plan of one of the supports for the guide roller which is indicated in Fig. 1.

I will now describe the machine illustrated. Upon suitable framework and carried in bear-

ings I arrange a first motion shaft 1 with fast and loose pulleys 2, 3 said shaft carrying cone pulleys 4 which drive other cone pulleys 5 at the front of the printing machine said pulleys 5 being mounted on a shaft 6 as shown in Figs. 6 and 7. The shaft 6 has a spur pinion 7 gearing into another pinion 8 which drives a third pinion 9 the pinion 9 driving the 1st revolving die or printing cylinder 10. The printing cylinder 10 is an engraved cylinder 15 and is carried on trunnions or centers 11, 11^x which fit in coned ends on the printing cylinder. Such trunnions or rather the carriers thereof are adjustable. The one on the left has its carrier set up by an adjusting screw 12 and the one on the right by an adjusting device 13. The trunnions are really two longitudinally adjustable centers and all the parts are carried in the adjustable bearing supports 14, 14 movable on the slides 15, 15. A driving connection requires to be established between the disk 18^x carrying the trunnion 11 on the left and the printing cylinder, and this may take the form of a disk with pins 16, 16 on opposite faces, the said pins entering holes 30 in the disk 18^x and the printing cylinder 10 (see Fig. 5). The position of these pins may be varied as required to suit the printing roller.

The printing cylinder 10 is adjusted circumferentially by rotating a worm wheel 17 which is fixed to the shaft 18 driving the cylinder 10, the spur pinion 9 being loose on the boss of the worm wheel 17 and locked to the worm wheel by means of a worm 19, and such worm 19 is rotated as required to turn the worm wheel 17 and impart the desired angular movement for adjusting the cylinder 10 circumferentially. Ordinarily the worm wheel 17 is locked to the gear wheel 9 by the worm 19 and the three revolve as a solid piece as will be understood. Fig. 5 indicates the parts sufficiently clearly. This identical motion is fitted to the 2nd printing cylinder 10^x, and likewise the endwise adjusting means.

To drive the 2nd printing cylinder I use an upright shaft 20 supported in suitable bearings and to actuate this shaft a miter wheel 21 on the shaft 6 drives a miter wheel 22, similar miter wheels 23, 24 occurring at the top, and so the shaft 25 is driven and the pinion 26 which is the equivalent of the pinion 7, and this pinion 26 drives the pinion 27 the equivalent of the pinion 9 and this pinion 27 carries the worm adjusting gear for circumferential or angular setting, and its center is the one where the endwise adjusting means for adjusting the printing cylinder longitudinally are located. The side stand-

ards 28, 28 carry the 2nd printing cylinder 65 10^x and all the attendant gear, as indicated by Figs. 1 and 6.

The doctor blades 29 (in Figs. 3 and 4) hold and support the color against the printing cylinders and such blades are conveniently held in a clamp 30 having trunnions 31 which fit bearing blocks 32 (Fig. 2) each block being adjustable by screws 33. The face of each doctor blade fits below the particular printing cylinder and the intervening space forms a trough for the color which is somewhat thick. Each doctor plate has slotted tails 34 toward each end and through the slots a clamping stud 35 (see Fig. 5) passes, having a thumb-nut 36 to permit adjustment and to enable the doctor blade to be held against the printing cylinder with the desired degree of pressure. The Figs. 2, 3 and 4 show the details as to the doctor blades 29 and the manner of carrying same.

The rollers or drums 37, 37 against which the paper is printed, by the 1st and the 2nd printing cylinders 10 and 10^x, are carried in bearing blocks 38, 38 the bases of which fit planed ways or slides 39 and such bearing blocks carry nuts 40. Fixed to the slides are bearings 41 for screwed spindles 42 and such screwed spindles engage said nuts 40 and carry at the other extremity each a miter wheel 43. In bearing arms 44 is supported a cross-shaft 45 fitted with miter wheels 46, gearing with the miter wheels 43, and said shaft 45 carries a hand-wheel 47 by rotating which the shaft 45 is turned and the miter gear actuated, with result, that the screws 42 are rotated and advance or retract the bearing blocks 38 and consequently the rollers or drums 37 as required. This motion for setting the backing roller 37 occurs with relation to the backing roller 37 of the second printing cylinder as Fig. 9 clearly indicates.

Owing to difficulty in dealing with the paper to be printed on, it is desirable to make provision to adjust the guide bars, such as 48 and 48^x, out of a truly horizontal position and I therefore so mount some, or all the guide bars, that they can be suitably inclined from the horizontal if required, and with this object I carry same in the way indicated by Fig. 10. In this figure the guide bar 48 is pivoted at the point 49 to a bracket 50 bolted at 51 to one of the side standards 28 while the opposite end of the guide bar has a sliding boss or ring 52 slidably engaging a screwed spindle 53 on a bracket, attached to the other side standard 28, the position of the boss or ring 52 being regulated by lock nuts 54, 54 whereby the position of guide bar 48 can be adjusted as required. The other bar 48^x is carried in a similar manner. The guide roller 55 is also preferably so supported as that either end may be adjusted horizontally or verti-

cally and for this purpose such guide roller 55 is supported at each end by compound brackets. Such brackets cannot be well shown in Fig. 1 but are indicated by Fig. 11 5 which is a plan partly in section.

The main bracket 56 is bolted to the side standard 28 and supports a vertically adjustable bracket 57 moved by an adjusting screw 58, while the roller 55 sits in bearings 10 formed in a bracket 59 adjustable horizontally on the brackets 57 by an adjusting screw 60. This arrangement is the same at both ends and provides for the requisite horizontal and vertical adjustment.

15 When printing, the paper P is drawn from a batch such as 61 over one or more suitable stay bars or guides such as that marked 48 and then passes to the backing drum 37 against which it is printed by the printing 20 cylinder 10 with the first color, and then it is taken over the guide bar 48^x to the back of the machine where it is passed over a large roller 62. This roller is preferably adjustable and is so shown in Fig. 1 where the 25 bearing blocks 63 are adjusted by screws 64 engaging suitable nuts in connection with the bearing blocks. From the roller 62 the paper P bearing the 1st-imprint is conveyed partly around the roll 55 toward the 2nd 30 backing drum 37, it having undergone a sufficiently long traverse to allow the color to set sufficiently. Passing around the 2nd backing drum 37 the 2nd printing cylinder 10^x prints on the paper P the second color. 35 Leaving the 2nd backing drum the paper P passes over a supporting bar 65 and is then batched on a roller 68 or otherwise disposed of. The supporting bar 65 may be arranged horizontally or at any required angle to the 40 horizontal. To enable this to be done it has a shank piece 66 bored through and a stud 67 serves to lock the guide bar when swiveled to the required position, the stud 67 serving as the center. The large guide 45 roll 62 is preferably driven, as well as the batching roll 68. This can be done by having sheaths or pulleys on the guide roll 62 and on the batching roll 68, and driving by corresponding sheaths on the 1st motion 50 shaft 1. Fig. 8 indicates at 69 the sheaths which are fixed on the shaft of the guide roll 62 and a driving band 70 actuates the spindles from sheaths 71 on the 1st motion shaft 1. The spindle of the batching roll or 55 shaft 1 carries sheaths 72 driven by a band 73 from sheaths 74 on the 1st motion shaft 1, as shown also in Fig. 8.

The colors to be printed may be kept hot by a gas jet or jets below the doctor blades 60 and I indicate a gas burner in Fig. 3 the same being lettered 75.

I declare that what I claim is:

1. In a color printing machine for printing transfer papers in two colors, guides for the

paper, a backing roller, a printing cylinder, 65 a color supporting and adjustable doctor blade, gear driving means for said printing cylinder, endwise adjusting means for said cylinder, worm gear allowing circumferential adjustment of said cylinder, paper guiding 70 devices insuring a long traverse, a second backing roll, a second printing cylinder, endwise adjusting means for said cylinder, worm gear for circumferential adjustment, and a batching device batching up the two color 75 printed paper, as set forth.

2. A color printing machine for printing transfer paper in two colors having adjustable guides for the paper to be printed, clamping means for fixing said guides, a 80 backing roller, bevel adjusting gear for the same, a printing cylinder, a doctor contacting therewith, clamping means for said doctor, gear for driving the printing cylinder, guides for insuring a long traverse to the 85 paper, a second backing roller, bevel adjusting gear, a second printing cylinder, a doctor contacting therewith, clamping means for said doctor, gear wheels for driving the second printing cylinder, a paper guide, and 90 a batching device as set forth.

3. A color printing machine for the purpose specified, having adjustable guides for the paper, clamping means for holding said guides when adjusted, a backing roller, bevel gear actuated setting-up means, a printing cylinder, endwise adjusting means, worm gear for circumferential adjustment of said cylinder, traversing guides for the paper, a 95 second backing roller, bevel adjusting gear, 100 a second printing cylinder, endwise adjusting gear, worm adjusting gear, paper guiding means, and a driven batching roller as set forth.

4. In a color printing machine, a first 105 motion shaft, a shaft driven therefrom, a printing cylinder, gear wheels actuating the printing cylinder, endwise adjusting means therefor, worm gear for circumferential adjustment of said cylinder, an upright shaft, 110 miter gear, and pinion driving mechanism for a second printing cylinder, a second printing cylinder, endwise adjusting gear, worm gear for circumferential adjustment of said second cylinder, backing rollers for the 115 paper to be printed, coupled bevel adjusting gear for the backing rollers, paper guiding means and a taking-up device as set forth.

5. A color printing machine for printing paper with a transfer design in two colors 120 having adjustable guides, slotted guides in brackets for said guides, clamping means, a backing roller, bevel adjusting gear therefor, a printing cylinder, adjusting means therefor, a doctor contacting with the cylinder, 125 adjusting means for the doctor, means for insuring a long traverse to the paper leaving the first printing cylinder, a second backing

roller, bevel adjusting gear for the roller, a second printing cylinder, toothed driving gear therefor, adjusting means for the second cylinder, final guiding means for the paper and taking-up means, all for the purpose and as set forth.

In testimony whereof I have signed my

name to this specification in the presence of two subscribing witnesses.

WILLIAM BRIGGS.
